UNITED STATES PATENT OFFICE.

CLIFFORD O. DICKEY, OF PORTLAND, OREGON.

RAZOR-BLADE SHARPENER.

Application filed August 10, 1925. Serial No. 49,373.

This invention relates to an improvement in razor blade holders, in the use of which the blade of a safety razor may be conveniently and securely held to permit convenient handling of the blade for sharpening or other like purposes.

The holder of the present invention comprises pivotally connected blade engaging members adapted to be moved into aligned relation to hold the blade between them, or to non-aligned relation to permit convenient removal or application of the blade, each of the members being terminally formed with a threaded projection, which projections, when the members are in blade holding positions, form a threaded stud to be engaged by a handle, which when applied compels a slight clamping cooperation of the members and holds them rigidly in aligned positions.

Fig. 1 is a plan view of the holder, a blade being shown in position.

Fig. 2 is an edge view of the same the handle and holder proper being shown separated.

Fig. 3 is a plan view of the holder with the members arranged in such relative positions as to permit the application or removal of the razor blade.

Fig. 4 is a transverse section through the holder.

The improved holder includes what may be termed a holder proper 1 and a handle 2 with such parts adapted for connection or disconnection at will as will later appear.

The holder proper comprises two members 3 and 4 of substantially identical size and shape, that is having a length exceeding that of the blade 5 with which they are to cooperate, and being semi-oval in transverse section with a major dimension materially less than the width of the blade. The members are pivotally connected at one end as at 6, so that they may be moved into alignment as indicated in Fig. 4, or into a relatively offset position, as indicated in Fig. 2. One of the members is provided with studs 7, appropriately arranged to cooperate with the usual opening 8 formed in the blade 5, and the other member is formed with transverse channels 9 to receive the ends of the studs as the members are moved into blade holding relation.

At the ends opposite the pivotal connection the members are formed with a half-circular stud or projection 10, which when the members are in blade holding position will together form a circular stud exteriorly threaded to cooperate with a threaded bore 11 in the handle 2. Preferably the members are so disposed that when in blade holding relation the proximate surfaces are slightly spaced apart, so that in applying the handle a slight pressure is required on the members of the holder proper to move the stud sections together. This results in a clamping action on the blade to increase the holding effect.

The application in use of the holder, both as to the insertion and removal of the blade is readily apparent, it being understood that the portions of the studs 7 which project above the surface of the blade 5 when the latter is in position on the studs, are received in the transverse channels 9 of the cooperating member.

Of course, the blade engaging means, here shown as studs and recesses, will be of that specific construction necessary to cooperate with the particular type of safety razor blade for which the holder is designed. Any appropriate material may be used for the holder, and its dimensions may be such as requisite for the particular razor blade.

I claim:

A razor blade holder, comprising a holder proper and a handle designed for removable connection therewith, the holder proper comprising members connected at one end for swinging in a plane parallel to the blade to be held between the members, one of said members being formed with projections to engage openings in the blade and the other of said members being formed with channels extending transverse and throughout the full width of the member to receive the studs when the members are disposed in blade holding relation, the free ends of the members being threaded to cooperate with the threaded socket on the handle.

In testimony whereof I affix my signature.

CLIFFORD O. DICKEY.
